DAVID LANDAU, OF NEW YORK, N. Y.

LAMINATED SPRING.

1,199,038.

Specification of Letters Patent. Patented Sept. 19, 1916.

Application filed January 30, 1915. Serial No. 5,181.

To all whom it may concern:

Be it known that I, DAVID LANDAU, a citizen of the United States, residing at 23 Mount Morris Park west, county of Bronx, 5 State of New York, have invented certain new and useful Improvements in Laminated Springs, of which the following, taken in connection with the accompanying sheet of drawings, is a full, clear, and concise 10 description thereof.

The present invention relates to certain new and useful improvements in the construction of those springs which are built up from a series of superposed leaves and 15 are usually termed laminated springs; the primary object of the invention being to provide a spring of this character which embodies novel features of construction whereby danger of failure by breakage of 20 the master leaf brought about by the fatigue of material is reduced to a minimum.

A further object of the invention is to provide a spring of this character in which the initial internal tension produced in the 25 spring leaves by banding or bolting the several leaves together when assembling the same is minimized, the spring being thereby enabled to have a much greater range of deflection.

30 The invention still further contemplates the provision of a spring embodying the same principle of construction and designed to flex in opposite directions or take up the rebound in an effective manner without producing dangerous stresses in the master leaf 35 which is subjected to reversal stresses.

With these and other objects in view, the invention consists in certain novel combinations and arrangements of the parts as will 40 more fully appear as the description proceeds, the novel features thereof being pointed out in the appended claims.

For a full understanding of the invention, reference is to be had to the following description and accompanying drawings, in which,

Figure 1 is a side elevation of an assembled laminated spring constructed in accordance with the invention. Fig. 2 is a 50 similar view showing the position of the assembled leaves before being nipped and clamped together at their central point. Fig. 3 is a side elevation of a spring constructed in accordance with the invention and embodying a slight modification. Figs. 4, 5 and 6 are similar views showing additional

modifications. Fig. 7 is a side elevation of a spring constructed in accordance with the invention and provided with a counter-spring to take the rebound. Fig. 8 is a side elevation of a spring constructed in accordance with the invention and designed to flex in opposite directions. Fig. 9 is a view showing the various leaves of the spring illustrated by Fig. 8 in the position assumed 65 before being nipped together and clamped at their central portion. Fig. 10 is a side elevation of a spring designed to flex in opposite directions, but to resist a greater load in one direction than in the other direction, and Fig. 11 is a view showing the various spring leaves of the construction illustrated by Fig. 10 in the position assumed 70 before being nipped together and clamped at their central portion.

75 Corresponding and like parts are referred to in the following description and indicated in all the views of the drawings by the same reference characters.

In the art of making leaf springs it is 80 customary to give to the individual spring leaves different degrees of curvature, as roughly indicated by Fig. 2. The degree or amount of curvature also usually increases from the master leaf to the smaller leaves, 85 and when the spring is built up of a considerable number of leaves, a few of the shorter leaves are usually formed with the same curvature. When the spring leaves are 90 nipped together and clamped at their central point the master leaf is flexed in a negative direction, that is, in a direction opposite to that produced when the spring is acted upon by an external load. Where the master leaf is made of the same thickness 95 or even of a thicker section than the shorter leaves, as is the more usual case, this initial negative stress in the master leaf produced by the nipping or banding together of the 100 spring plates, may be very considerable, and this negative stress or deflection must be counteracted by equal and opposite stresses or deflections in either all or some of the remaining spring leaves. When the spring is placed under a load and flexed in the 105 usual manner, the negative stress in the master leaf is first overcome and a positive stress subsequently produced therein. The range of the stresses to which the main leaf or leaves are subjected thus includes both 110 positive and negative stresses, and it is an established fact that where the range of

stress is from tension to compression and back again, failure of the metal from fatigue may be expected much sooner than would otherwise be the case. The safe 5 range of deflection is thereby decreased. Where the master leaf is made thicker or the same thickness as the remaining leaves, the initial internal negative stress produced therein by nipping the spring plates together is comparatively large so that not only is the ability of the master leaf to resist rebound decreased, but the range of the stresses from tension into compression and back again as the spring is loaded and un-loaded, is such as to render the spring subject to early failure by rupture brought about by the fatigue of the metal due to the large initial internal stress. In order to avoid this difficulty and to reduce the initial 10 internal stress caused by "nipping" it is proposed to make the master leaf or leaves thinner than the other leaves.

Referring to Figs. 1 and 2, the numeral 1 designates the master leaf and 2 the short leaf, a series of leaves 3, 4 and 5 being interposed between the master leaf and the short leaf. These several leaves are shown gradually thicker and shorter from the master leaf to the short leaf and the conventional band 6 may be provided for holding the leaves together at their central point. Several of the longest leaves may, however, be of the same length, and likewise several 30 may be of the same thickness as shown in 35 Figs. 3 to 6 inclusive. In fact, all but the master leaf or leaves may have the same thickness—the master leaf or leaves being thinner. The individual leaves are initially formed with different degrees of curvature, 40 as indicated by Fig. 2, the master leaf 1 having a smaller degree of curvature than the adjacent leaf and the degree of curvature increasing through the successive leaves, with the exception of a few of the 45 shorter leaves which may have the same degree of curvature and fit closely together. Where the number of plates is few, all leaves, 50 may have different curvature.

When the several leaves are nipped together and secured at their central point by the band 6, or an equivalent device, the amount of the arch or "camber" of the master leaf 1 is increased, the ends thereof being deflected in a direction away from the body 55 of the spring while the central portion thereof is deflected in an opposite direction, or toward the body of the spring. This initial flexing of the master leaf 1 is directly opposite in sense and direction to the flexing produced therein when a load is applied to the ends thereof in the usual manner. In other words, the stresses produced in the master leaf 1 by the "nipping" operation 60 are exactly the reverse of the stresses produced therein under the action of a load.

This initial stress may consequently be termed a negative stress, as opposed to the normal or positive stress produced by the action of a load. However, by changing the thickness of the master leaf 1 and making it thinner than the other leaves, the amount of internal initial negative stress produced therein is made comparatively small so that the spring may be flexed over a greater range without fear of breaking the master leaf. Furthermore, since the force or pressure required to hold the master spring leaf 1 in its flexed or distorted position after being "nipped" must be resisted by equal and opposite stresses in the other spring leaves, the reduction of the initial stress in the master leaf also results in a reduction of the initial stresses in all of the leaves, thereby further increasing the efficiency of the spring as a whole so that the spring will last much longer than the conventional forms of springs now in use. Such a spring may be composed of several thin leaves comprising in effect the master leaf in combination with successively shorter leaves thicker than the thin leaf or leaves and either all of the same thickness, from the longer leaves to the shortest leaf, or, gradually increasing in thickness from the longer leaves to the shorter leaf, or several leaves may have the same thickness. Furthermore, the leaves of the spring may be either tapered or not and the tapers may either be uniform or of gradually increasing lengths from the shortest leaf upward to the longest leaf or even vice versa.

In Fig. 3 I have shown a form of the spring in which the numerals 10 and 11 designate two thin leaves which form in effect the master leaf, the leaf 10 being provided at the ends thereof with conventional eyes, 16. The successive leaves 12, 13 and 14 arranged under the thin leaves 10 and 11 are all of the same thickness and gradually decrease in length from the longest spring leaves 10 and 11 to the shortest spring leaf 15. The long leaf 11 is of equal length but thicker than the individual lamina of the master leaf and its ends are tapered while the thicker leaves 12, 13, 14 and 15 are not tapered, and the spaces between the ends of the leaves may either be of the same length or of gradually increasing lengths, measured from the master leaf downward to the short plate, as desired. As has been heretofore explained, by forming the master leaf of one or more thin strips, the negative stresses produced therein by the flexing brought about by the "nipping" operation are comparatively small so that the efficiency of the spring as a whole is increased and a greater range of deflection made possible, without danger of the master leaf being caused to rupture because of initial stress fatigue of the metal. Since greater deflection implies

greater loads, it follows then that such springs can carry with equal safety greater loads.

In Fig. 4 is shown a slight modification in which the long spring leaves 10^a and 11^a 11² are formed of thin material while the spring leaves 12^a, 13^a, 14^a and 15^a are formed of thicker material. The construction is substantially the same as that shown by Fig. 3, with the exception that the ends of the thicker spring leaves 12^a, 13^a, 14^a and 15^a are tapered. The conventional eyes 16^a are provided at the ends of one lamina of the master leaf, and a conventional clip, or band, or its equivalent, 17^a may be provided for holding the spring leaves together.

Fig. 5 shows a further slight modification in which the two longer leaves 10^b and 11^b are formed of thin material and of the same thickness, while the long leaf 11² and the leaves 12^b, 13^b, 14^b and 15^b gradually increase in thickness from the longer to the shorter leaf and have tapered ends. Also several of these leaves may have the same thickness. The conventional eyes 16^b are provided at the ends of top leaf or lamina of the master leaf and a suitable clip, or band, or its equivalent 17^b may be provided for holding the leaves together. The spaces between the ends of the spring leaves may be either of a uniform length or of a gradually increasing length measured from the master leaf downward as found most desirable.

Fig. 6 illustrates a further slight modification in which 10^c and 11^c indicate two thin spring leaves constituting in effect a master leaf. The next succeeding leaves 11², 12^c, 13^c and 14^c gradually, or rapidly increase in thickness, or several leaves may remain of the same thickness, while the two shorter spring leaves 14^c and 15^c may be of the same thickness. Seats 16^c are provided at the ends of the master leaf and a clip, or band, or its equivalent, 17^c may be provided for holding the spring leaves together at the center of the spring. In this construction the master leaf is formed of several thin strips of material, a number of the shorter leaves are of the same thickness, while the following leaves gradually or rapidly increase in thickness from the master leaf to the shorter leaves.

All of the various modifications shown by Figs. 3, 4, 5 and 6 operate in substantially the same manner and have the added advantage, as has been explained, of increasing the possible range of deflection, rendering failure of the master leaf by fatigue improbable, and giving the spring increased ability to resist rebound.

The construction of a spring with a thin master leaf and thicker supporting leaves is disclosed in and forms a part of the subject-matter of my companion application,

Serial No. 92,446, filed April 20th, 1916, which is a continuation in part of a previous application, Serial No. 861,951, filed September 16th, 1914. The use of the thin master leaf is also covered broadly by the claims of my said application, Serial No. 92,446. For this reason, I do not claim this construction by itself herein but the present case relates to an adaptation of such broad features of construction set forth in said application as used in connection with certain other features so as to produce a spring specially fitted for certain uses, particularly where the spring is required to withstand considerable deflections in opposite directions. As explained above, the capability of the spring to withstand reversal stresses due to rebound or other deflection reversals is greatly enhanced by the use of a thin master leaf, which also diminishes the initial stresses due to nip. The ability to withstand reversal stresses may further be enhanced by the use of a counter spring or supplemental spring leaves, on the opposite side of the thin master leaf from the main supporting plates as will now be more fully described and it is to these features of construction that the invention forming the subject-matter of the present application more particularly relates.

Notwithstanding the increased ability of the spring to resist rebound without danger of breaking the master leaf, it may under some conditions be desirable to provide counter-springs, as indicated by Fig. 7. Where such counter-springs are used, however, they can be made of lighter material and more flexible than has heretofore been the case, since a greater part of the force of the rebound may by this construction be taken up by the main spring master leaf.

Referring to Fig. 7, the numeral 20 designates the master spring leaf which is of thin material and the numerals 21, 22 and 23 the other spring leaves which may gradually increase in thickness and decrease in length from the master leaf to the short leaf. The counter-spring is arranged in a reverse order and includes the spring leaves 24, 25 and 26. A spacing block 27 is arranged between the counter-spring and the main spring and the various members are held together by a suitable clip 28. The main spring is constructed and designed to act in substantially the same manner as has been previously explained in connection with the other embodiments of the invention. The ends of the counter-spring project over the main spring on opposite sides of the center thereof and are normally slightly spaced from the main spring. However, when the ends of the main spring are flexed upwardly by the rebound they are brought into engagement with the ends of the counter-spring so as to bring the counter-spring into

action. Ordinarily these counter-springs must be made strong and stiff, since the ability of the master leaf of the main spring to resist the rebound has been very greatly reduced by the comparatively large negative stresses produced therein by the "nipping" operation. With my construction, however, the effective strength of the master leaf to resist the rebound is not greatly reduced by the negative stress produced by "nipping" and the counter-spring may accordingly be made lighter and more flexible. In other words, the leaves of my main spring can reverse and flex upwardly with greater safety than leaves of springs where the main leaves are either thicker than or of equal thickness with the shorter leaves. There also frequently arises in the art the need for a spring constructed to flex in opposite directions under the same or unequal loads. Such a spring will have the stress reversed in its main plate, and in all the clipped plates where such are used, and the most efficient spring, therefore, is one in which the main plate, and clipped plate have a small, negative stress. The ordinary counteracting or rebound spring has a very heavy main leaf and of necessity the negative stress produced therein by "nipping" is quite large, the result being that trouble is usually brought about by rupture of this master leaf. This difficulty may be eliminated by a construction such as is shown by Figs. 8 and 9. The numeral 30 designates the thin master leaf which is provided at the ends thereof with the usual eyes, or their equivalent, 31. Arranged upon opposite sides of the master leaf 30 are the two sets of successively thicker and shorter leaves 32, 33 and 34, each set of the leaves being identical since the spring is designed to carry substantially the same loads in both directions. With the exception of the master leaf 30, the various leaves are individually bent, as indicated by Fig. 9, before assembling. When the leaves are bolted together they may be secured at their central point by a suitable bolt 35. With a balanced spring such as is shown there will be no initial stress put upon the master leaf 30 and the master leaf will thus flex in one direction as readily as in the opposite direction without difference of stress therein. With a thin master leaf, however, the range of deflection is greater than with a thick master leaf, since the same amount of deflection produces less stress in a thin leaf than in a thicker one. The range of positive and negative stresses thus produced in the master leaf is less for a given amount of deflection than would be required in a thicker master leaf, and the danger of rupture from fatigue is thus decreased.

Where the spring is designed to take unequal loads in opposite directions, a con-

struction such as is shown by Figs. 10 and 11 may be used to advantage. The numeral 40 designates the master leaf which is provided with the usual eyes, or equivalent, 41, at the ends thereof. Arranged upon one side of the master leaf 40 are the successively thicker and shorter spring leaves 42, 43 and 44, while arranged upon the opposite side of the master leaf 40 are the opposed spring leaves 45 and 46. The spring leaves 42, 43 and 44 are longer than the spring leaves 45 and 46; these leaves are designed to coöperate with the master spring leaf 40 to take the heavier load, the spring leaves 45 and 46 in conjunction with the master leaf 40 taking the lighter and reversed load.

The individual spring leaves may have a preliminary curvature, as indicated by Fig. 11, although after being assembled they are nipped together and secured by the conventional bolt or its equivalent, 47. The master leaf 40 is thus bowed less when free, which puts an initial stress in it, said stress being in the direction of the upward-acting and small load. The initial internal stress produced by "nipping" thus decreases the strength of the master leaf to resist the force of the lighter load, but by making the master leaf of thinner material this objection is reduced to a minimum. The stress produced in the thin master leaf by "nipping" is consequently much smaller than would be produced in a thick master leaf, and this has the advantage of enabling the spring to be used for a greater range of flexure in both directions. This amounts to substantially the same thing as saying that more energy can be stored, greater resilience obtained, and greater loads carried safely without fear of danger to the main or master leaf.

With the conventional form of spring the master leaf is made of the same thickness or thicker than the shorter leaves, with the result that failure of the spring is usually brought about suddenly and often unexpectedly by rupture of the master leaf. Where the master leaf fails the spring is rendered completely useless and this failure usually comes without warning and at an inopportune time. With the above construction, however, one of the shorter leaves will usually break in advance of the master leaf, thereby giving warning of the fact that the spring is in a dangerous condition before complete failure of the spring results. It has been attempted in the past to improve upon the conventional construction of these springs by using better material for the master leaf than for the other leaves, although such springs are more costly and have never fully accomplished the desired results. By making the master leaf of thinner material than the other

leaves the range of deflection is increased, the danger of failure of the main leaf of the spring from fatigue of the metal is reduced to a minimum, the ability of the 5 spring to resist rebound increased, and a construction provided which has great resilience and will safely carry greater loads.

Having thus described my invention, what I claim as new and desire to secure by Letters Patent, is:—

1. A spring built up of superposed leaves and formed with a thin master leaf and thicker supporting leaves applied to opposite sides thereof.
- 15 2. A spring built up of superposed leaves and embodying a thin master leaf and thicker supporting leaves on opposite sides of said master leaf there being more supporting leaves on one side of the master leaf than on the other, some of the leaves on the former side of the master leaf being of greater length, than the longest leaves on the other side of the master leaf.
- 20 3. A spring built up of superposed leaves and formed with a thin master leaf and thicker supporting leaves, a number of the leaves being originally formed with different degrees of curvature so that small internal initial stresses are produced therein when they are clamped together and a counter-spring mounted in co-operative relation with the main spring to take up the rebound.
- 25 4. A spring built up of superposed leaves and formed with a thin master leaf and thicker supporting leaves, a number of the leaves being formed individually with different degrees of curvature so that small internal initial stresses are produced in the master leaf therein when the leaves are clamped together, in combination with a

similarly constructed counter-spring having an opposed relation thereto.

5. A spring built up of superposed leaves and formed with a thin master leaf and 45 thicker supporting leaves, a number of the leaves being individually bent so that small internal initial stresses are produced therein when they are clamped together, in combination with a smaller and similarly constructed counter-spring having an opposed relation and mounted with the ends thereof normally spaced from the main spring.

6. A spring built up of superposed leaves and formed with a thin master leaf and 55 thicker supporting leaves applied to opposite sides thereof so that the spring may be safely flexed in opposite directions, certain of the leaves being individually curved so that small internal initial stresses are produced therein when the leaves are clamped together.

7. A spring built up of superposed leaves and formed with a thin master leaf and unequal numbers of thicker supporting leaves 65 applied to opposite sides thereof so as to provide a spring adapted to flex in both directions and carry a greater load in one direction than in the opposite direction, certain of the spring leaves being originally 70 formed with a curvature so that small internal initial stresses are produced therein when the spring leaves are clamped together.

In witness whereof I have hereunto set 75 my hand in the presence of two subscribing witnesses.

DAVID LANDAU.
